G. C. STACEY

SAND EXTRACTOR

Filed Sept. 11, 1923

By A. L. Jackson
Attorney

UNITED STATES PATENT OFFICE.

GROVER C. STACEY, OF DALLAS, TEXAS.

SAND EXTRACTOR.

Application filed September 11, 1923. Serial No. 662,154.

To all whom it may concern:

Be it known that I, GROVER C. STACEY, a citizen of the United States, residing at Dallas, in the county of Dallas and State of Texas, have invented certain new and useful Improvements in Sand Extractors, of which the following is a specification.

My invention relates to sand extracting devices and more particularly to devices for cleaning sand or dirt from the suction draft in cotton cleaning and elevating devices; and the object is to provide a simple and useful extracting device for use of cotton ginners, which is interposed in the suction line of a cotton cleaning and elevating apparatus wherein the cotton is elevated by a suction fan. Throughout the cotton regions of the United States and more particularly in the sandy sections of the country in the States where cotton is raised, the ginners have experienced a great loss by reason of the sand passing through the suction line into the fan, and the fan, running at a high rate of speed, throws the sand against the scroll sheet of the fan, cutting out the blast wheel and suction sheets. In some instances they have been known to cut them out in three days, necessitating the spending of a great deal of money to replace the blast wheel and scroll sheets of the fan. The apparatus hereinbelow described is interposed in front of the fan and extracts the sand from the air before the air passes through the fan. The object of this invention is to provide a simple device by which the sand can be separated from the suction draft at small cost and the sand may be separated from the draft without any additional suction lines. Other objects and advantages will be fully explained in the following description, and the invention will be more particularly pointed out in the claims.

Reference is had to the accompanying drawings which form a part of this application.

Fig. 1 is a side elevation of the sand cleaner. Fig. 2 is a plan view of the lower part of the device, being a horizontal section, taken on the line 2—2 of Fig. 1. Fig. 3 is a broken vertical section, taken on the line 3—3 of Fig. 2.

Similar characters of reference are used to indicate the same parts throughout the several views.

The improvements herein shown are located in the suction pipe 1 which leads from

a cleaner 2 to a suction fan (not shown). The pipe 1 is intercepted for the purpose of interposing the sand cleaning devices. The pipe 1 is intercepted at 3 and at 4. A larger pipe 5 surrounds the end 6 of the main pipe for the purpose of forming sand or vacuum pockets for collecting the same. A cone-shaped deflector 7 is positioned above the open end of the pipe section 6 and held there by supports 8 which are attached to the pipe 6 and to the interior of the deflector. There may be any suitable number of these supports. An annular space about the pipe 6 within the pipe 5 is divided into two pockets by spiral partitions 9 and 10 which commence at the upper end of the pipe 8 (and each runs around 180 degrees) and terminate in pocket valves 11. The sand will strike the deflector 7 and be thrown into the vacuum pockets about the pipe 6. All the sand will fall or slide down to the valves 11. The air will be drawn under the deflector 7 into the upper end of the pipe 6 and go on out through the fan (not shown). The valves 11 are of cloth of the usual type and sand will accumulate until it becomes heavy enough to dump. The sand will be dumped by gravity, opening the valves 11. The valves will then close automatically, being aided by the suction through the pipe 6 and the suction fan.

Various changes in the construction, proportions and arrangement of the several parts may be made without departing from my invention.

What I claim, is:—

1. A device for extracting sand from a suction line comprising a suction pipe in sections spaced apart, a larger pipe surrounding and forming a sand pocket with one section and tapering to and connected to the other section, and a deflector positioned within said tapering section for throwing the sand into said pocket.
2. A device for extracting sand, a suction line comprising a vertically disposed suction pipe in sections spaced apart, a larger pipe surrounding the lower section and forming a pocket therewith and tapering to and connected to the upper section, and a deflector positioned within said tapering section for throwing sand into said pocket.
3. A device for extracting sand from a suction line, comprising a vertically disposed suction pipe in sections spaced apart, a larger pipe having a closed bottom and

valves therein and surrounding the lower section and forming a sand pocket therewith and tapering to and connected to the upper section, spiral partitions dividing said pocket and forming means for directing the sand into said valves, and a deflector positioned in said tapering portion for deflecting the sand into said pocket.

4. A device for cleaning sand from a suction line comprising a vertically disposed suction pipe operatively connected with the cotton cleaner and being in sections spaced apart, a larger pipe surrounding a portion of the lower section of said suction pipe and forming a vacuum pocket and tapering to and connected to the upper section of said suction pipe, a bottom for said larger pipe and discharge valve in said bottom, spiral partitions dividing said pocket and forming means for directing sand to said valve and a deflector mounted in said tapering portion for directing sand into said pocket.

5. A device for extracting sand from the suction line of a cotton cleaning and elevating apparatus comprising a suction pipe in

sections spaced apart and operatively connected to a cotton cleaner and the suction fan, a larger pipe surrounding the fan section of said pipe and forming a sand pocket therewith and tapering to and connected to the other section of said pipe, and means mounted between the said sections and within said tapering pipe section for deflecting sand into said pocket.

6. A device for extracting sand from the suction line of a cotton cleaning and elevating apparatus comprising a suction pipe operatively connected to a cotton cleaner and to a suction fan and being in sections spaced apart, a larger pipe surrounding a portion of the fan section of said pipe and forming a sand pocket therewith and tapering to and connected to the other portion of said pipe, dumping valves for said pocket, and means positioned between the sections of said suction pipe for deflecting sand into said pocket.

In testimony whereof, I set my hand, this 31st day of August, 1923.

GROVER C. STACEY.
